UNITED STATES PATENT OFFICE.

JAMES E. FAHY, OF PROVIDENCE, RHODE ISLAND.

VALVE.

SPECIFICATION forming part of Letters Patent No. 415,863, dated November 26, 1889.

Application filed September 1, 1888. Serial No. 284,346. (No model.)

To all whom it may concern:

Be it known that I, JAMES E. FAHY, of Providence, in the county of Providence and State of Rhode Island, have invented certain new and useful Improvements in Valves, of which the following is a full, clear, and exact description, reference being had to the accompanying drawings, forming part of this specification.

10 My invention relates to valves used in flushing water-closet basins.

The object of my invention is to control the descent of the valve by means of an air-chamber provided with a flexible diaphragm and a 15 regulating-valve.

To the above purposes my invention consists in the certain novel combinations of the different features, as hereinafter fully described and claimed.

20 In the accompanying drawings, Figure 1 is a sectional view of my improved device as applied to the top of the overflow-tube. Fig. 2 is a sectional view of my improved device as applied to the outside of a tank supplied with 25 the old form of valve. Fig. 3 is a sectional view taken on the line 3-3 of Fig. 1, looking down, to clearly show the cross guide or stop. Fig. 4 is a sectional view taken on the line 4-4 of Fig. 1, looking down, to clearly show the 30 support for the operating-rod.

In the said drawings, like numbers of reference designate corresponding parts throughout.

Referring to the drawings, 5 designates the 35 pull-chain; 6, the pivoted lever; 7, the chain for connecting the lever to the overflow-tube; 8, the overflow-tube; 9, the weight; 10, the valve; 11, the valve-seat; 12, the nut for securing the valve to the weight 9; 13, the cross- 40 support forming part of the outlet-section 14. The operating-rod 15 is shown in Fig. 1 as secured to the support 13 at one end and to the diaphragm 16 at the other end. The guide 17 is secured to the operating-rod, and, as it is 45 provided with two or more arms, will act as a guide to the overflow-tube, and also as the ends will come in contact with the weight when the tube reaches its limit of travel it 50 will act as a stop, thereby preventing the diaphragm being extended too much and injured. The diaphragm 16 is securely held in place by means of the cap-piece 18, which is

made cup shape, so as to form an air-chamber in connection with the diaphragm. This cap-piece 18 is provided with the quick-acting 55 valve 19, the said valve 19 being held to its seat by a very light spring, so as to be readily moved. The regulator 20 is screw-threaded into a boss 22, formed on the cap-piece 18, said boss being provided with an inlet into the air-chamber and also with the hole or opening 21; or the fit in the screw-thread on the regulator may be sufficiently loose to allow of the air passing out therethrough fast or slow, according to the distance at which the regulator is 65 set from its seat.

The construction shown in Fig. 2 is the same in principal as that shown in Fig. 1, differing only in being located on the outside of the tank and having one end of the operating-rod 15 secured to the lever 6, thereby being movable instead of stationary, as shown in Fig. 1.

The operation of the device is as follows: Upon the chain 5 being pulled downward the 75 valve will be lifted off from its seat by reason of its connection with the chain through the lever and overflow-tube, the diaphragm will have been extended in the construction shown in Fig. 1, and the air-chamber filled 80 with air by reason of the valve 19 giving to the suction. When now the chain is released, the valve 19 will close by reason of the spring and pressure and the entire weight of the valve, overflow-tube, and the connecting 85 parts would be suspended were it not for the opening left at the regulator, and as the air escapes from the chamber by the regulator the valve will slowly descend to its seat and stop the flow of water from the tank. 90

In the construction shown in Fig. 2 upon the downward pulling of the chain 5 the diaphragm will have been depressed in the air-chamber, thereby forcing the air out of the chamber by reason of valve 19 being so 95 lightly held to its seat, and upon the limit of movement being reached and the valve 10 beginning to descend to its seat the valve 19 will be caused to close and air will be drawn into the air-chamber through the hole or 100 opening 21 and past the regulator until the valve 10 has reached its seat and the flow of water from the tank is stopped.

The device is simple in construction, is

easily applied to the old form of valve, and in no manner interferes with the proper working of the valve and its connecting parts.

In connection with my improved device 5 and the old form of overflow-tube I have shown a float device, the object of which is to entirely close the inlet-ports of the overflow-tube, so that no air can be sucked down with the water when the valve is in the raised 10 position, and that will float and rise when the valve is descending and gradually open the closed ports until the valve has reached its lowest position, when the ports will be wide open, so that in case of an overflow the 15 water can freely enter the overflow-tube and pass out through the outlet 14.

Two forms are shown, the constructions of which are as follows: That shown in Fig. 1 20 consists of a short piece of tube 23, having the ports 24 cut therein at sufficient distance from the top, so that when the float rests on the stop 25, which may be a ring secured to the outside of the overflow-tube 8, the upper portion of the closed tube will cover the ports 25 27 in the overflow-tube. Near the bottom of the tube 23 is attached the circular cup-shaped piece 26, which is open at the bottom and depends upon the air that will be confined therein upon its reaching the water for floating and lifting the tube 24. In the form illustrated in Fig. 2, instead of the cup-shaped piece 26, I show a closed chamber 28. It is evident, however, that instead of the floats 30 shown a piece of cork or other light material 35 having sufficient floating capacity to lift the tube may be attached to the bottom of the tube without departing from the spirit of my invention.

Having thus described my invention, I claim 40 as new and desire to secure by Letters Patent—

1. The combination, with the flushing-tank and the valve controlling the flow of the flushing-water, of a lever connected at one end with the valve to raise the same, and a device for controlling the descent of the valve, consisting of a rigid metal box provided with an automatic check-valve, a regulated air-passage, an elastic diaphragm extending across the open end of the metal box, and a rod secured to the center of the diaphragm, constructed to support the valve in the raised position, as described. 45

2. The combination, with a flushing-tank, of the lever 6, one end provided with a pull and the other connected with the overflow-tube, the overflow-tube 8, the valve 10, secured to the overflow-tube, weight 9, the ports 27, the tube 24, provided with the float 26, the rod 15, connected with the flexible diaphragm, stop 17, and an air-chamber provided with a flexible diaphragm, an automatic check-valve, and an adjustable air-passage constructed to control the descent of the flushing-valve, as described. 55

3. In a flushing-valve, the combination, with 60 the valve-seat 11, valve 10, secured to the overflow-tube, the overflow-tube 8, and cap-piece 18, of the screw-threaded regulator 20, and the check-valve 19 in the cap-piece 18, the diaphragm 16, secured across the open end of the 65 cap-piece 18, and rod 15, secured to the diaphragm, constructed to control the closing of the valve, as described. 70
